UNITED STATES PATENT OFFICE.

PAUL THEODOR BEIER, OF RODELHEIM, FRANKFORT-ON-THE-MAIN, AND FERDINAND BOCK, OF FRANKFORT-ON-THE-MAIN, GERMANY, ASSIGNEES, BY MESNE ASSIGNMENTS, TO UNITED SHOE MACHINERY CORPORATION, OF PATERSON, NEW JERSEY, A CORPORATION OF NEW JERSEY.

BUFFING-MACHINE.

1,280,639.

Specification of Letters Patent.

Patented Oct. 8, 1918.

Application filed May 31, 1913. Serial No. 771,051.

To all whom it may concern:

Be it known that we, PAUL THEODOR BEIER, a subject of the Grand Duke of Baden, residing at Rodelheim, Frankfort-on-the-Main, Germany, and FERDINAND BOCK, a subject of the King of Prussia, residing at Frankfort-on-the-Main, Germany, have invented certain Improvements in Buffing-Machines, of which the following description, 10 in connection with the accompanying drawings, is a specification, like reference characters on the drawings indicating like parts in the several figures.

This invention relates to machines for 15 removing material from stock and is herein illustrated in connection with a machine for buffing taps, soles, insoles, and similar articles.

It is at times desirable to roughen the 20 surface of a tap or sole so that the cement which is subsequently applied will secure a better hold; or again, it may be desirable to remove the grain from an insole so that it will be rendered more flexible and have 25 less tendency to crack when bent. Hitherto machines which have been used to perform these and analogous operations have required to be adjusted in accordance with the thickness of each piece of stock which 30 is to be fed to the machine.

The general object of the present invention is to provide a machine having buffing mechanism with means for causing said mechanism to remove a predetermined 35 amount of material from each piece of stock fed to the machine irrespective of the original thickness of said piece. The means referred to above may, if desired, be automatic and is so shown in the illustrative machine.

40 In machines of this general type it is common to provide a buffing roll and a presser between which the stock passes and feeding mechanism for advancing a piece of stock thereto. According to one feature of the invention, means are provided, responsive to 45 the thickness of the stock, for separating the presser and the buffing roll by a distance such that a predetermined amount will be removed from each piece irrespective 50 of its original thickness. In the illustrative machine a connection is provided between the presser and the feed mechanism for de-

termining the space between the presser and the buffing roll so as to accomplish this result.

55 In order that the same limit to the movement of the presser toward the buffing roll may be maintained throughout the entire buffing operation, another feature of the invention consists, in a machine having a 60 presser and front and rear feed members the positions of which determine the position of the presser, of a connection between said front and rear feed members whereby when one member is raised the other is raised 65 an equal amount. With this construction the limit to the movement of the presser toward the buffing roll is maintained throughout the entire buffing operation.

70 These and other features of the invention including certain details of construction and combinations of parts will be described in connection with an illustrative machine and pointed out in the appended claims.

75 Referring now to the accompanying drawings:—

Figure 1 is a front elevation of a machine in which the present invention is embodied;

Fig. 2 is a side elevation of the machine, the plate which covers certain of the gears 80 having been removed;

Fig. 3 is a plan of a portion of the upper part of the machine;

Fig. 4 is a section through that part of the machine shown in Fig. 3; and

Fig. 5 is a detail illustrating the linkage 85 which connects the upper feed rolls, the posts 31 being shown in cross section.

A standard 1 rising from the base of the machine is provided with bearings in which 90 is rotatably mounted a shaft 3, said shaft carrying a buffing roll 5 of any suitable type. Conveniently this roll may be a split roll, and in such case a hand wheel 7 fast to the shaft 3 enables the operator to hold the shaft 95 while the roll is turned to disengage the catch which holds the sections of the roll together. The rotation of this shaft is accomplished by a belt which passes around a pulley 9 on said shaft and around a large 100 pulley 11 on a counter shaft 13.

Above the buffing roll 5 is a table 15 provided with openings to expose the upper portion of said roll and the upper portions

of two lower feed rolls 17 (see Fig. 4). The shafts of these lower feed rolls are rotatably mounted in bearings in the table 15, and said table is angularly adjustable about the axis 5 of the shaft 19 of the rear lower roll 17, the adjustment being accomplished by means of a set-screw 21. Rising from the table are two guide rods 23, and slideable on these rods is an upper feed roll carrier 25 in which are 10 freely rotatable the shafts of the two upper feed rolls 27, said rolls being connected by mechanism shown best in Figs. 4 and 5 whereby the raising of one roll a given distance raises the other an equal distance.

15 Pivoted at 29 to the upper feed roll carrier 25 are two sets of posts 31; and rigid with and rising from the table 15 are two corresponding sets of standards 33. Two sets of links 35 are connected with these standards 20 by pivots 37 which pass through ears on the standards, and with the posts 31 by pivots 39. The links 35 of each set or pair are also pivoted together at their inner ends at 41 as well as to a slide block 43 which is located in 25 a vertical guideway in the upper feed roll carrier 25. With this construction it will be apparent that the raising or lowering of either one of the upper feed rolls imparts a similar and equal movement to the other, 30 and that if one feed roll is held above the table 15 a given distance the other will be held above it an equal distance.

The presser roll 45 is journaled in, depending arms of a presser roll carrier 47 35 which, like the feed roll carrier 25, is vertically slideable upon the rods 23 (see Fig. 1). Located above the presser roll carrier 47 and also slideable on the upright rods 23 is a bar 49 having four arms (see Fig. 3) 40 each of which is provided with an eye to receive the reduced upper end of one of the posts 31. This bar is constantly urged downwardly by springs 51 the tension of which may be varied by nuts 53; and between this bar and the presser roll carrier 47 45 is a spring 55, the tension of which may be varied by turning the adjusting screw 57. The extent of the downward movement of the presser roll carrier 47 is limited by stops 59 so that there is normally about one-sixteenth of an inch play, as shown in Figs. 1 50 and 2, between the upper surfaces of the portions of the feed roll carrier 25 which embrace the rods 23 and the adjacent lower 55 surfaces of the similar portions of the presser roll carrier 47. Normally, too, as shown in Fig. 4, the lowermost points of the upper feed rolls and the presser roll are substantially in the same plane.

60 With the construction thus far described, when a sole or similar article is fed to the forward feed rolls, the upper forward feed roll is raised a distance dependent upon the thickness of the sole, and at the same time

the upper rear feed roll is raised an equal 65 distance. The presser roll 45, however, is raised a less distance, owing to the play between the parts 25 and 47 referred to above so that the sole then raises this presser roll against the force of the spring 55. The 70 amount of material which is removed from the sole thus depends principally upon the position of the table 15 and to a slight extent upon the tension of the spring 55. It should be noted, however, that with a given 75 adjustment of the table 15 and the spring 55 the amount of material removed is predetermined and does not depend upon the thickness of the sole. The tension of the spring is ordinarily varied, by turning the adjusting screw 57, only when the quality of the stock which is to be fed to the machine is to be changed, that is, for a given quality of stock the screw 57 is properly set and receives no further attention until stock of a 80 different quality is to be operated upon. Although, as stated above, the tension of the spring 55 is ordinarily adjusted merely in accordance with the quality of stock which is to be operated upon, it is obviously possible to vary to some extent in this manner 85 the amount of material which shall be removed; and the tension of the spring is sometimes varied for this purpose, namely, to determine with nicety the amount of 90 material which is to be removed after the table 15 has been adjusted to determine the 95 amount roughly.

After the piece of stock emerges from between the rear feed rolls, it passes beneath a spring-pressed foot 61, the stem of which may be adjusted by turning a hand wheel 62, said foot being adapted to force the buffed surface of the piece against a brush 63 fast upon a shaft 65. This shaft carries 100 a grooved pulley 66 (see Fig. 3) around which and around a similar pulley 68 (see Fig. 1) on the counter-shaft 13 passes a belt not shown. A pulley 75 is fast upon a short shaft which carries a gear 67 (see Fig. 2), 105 said gear meshing with a gear 69 on the shaft of the rear lower feed roll; and from the latter gear is driven, through a train of idle gears 71, a gear 73 which is fast to the shaft of the forward lower feed roll. 110 The idle gears 71 are carried by a bracket on the table 15 as best shown in Fig. 1. The pulley 75 is driven from a small pulley 77 by means of a belt, said small pulley being fast to a shaft 79 which also carries a pulley 81 located in position to be driven by a belt from a pulley 83 on the counter-shaft 115 120 13. A blower 85 of any approved type has its rotary member mounted upon a shaft 87, said shaft also carrying a small pulley 89 which is adapted to be driven from a large pulley 91 on the counter-shaft. The rotation of the counter-shaft 13 is controlled in 125

the usual manner by a belt shifter to which is attached an operating handle 93.

In order to permit cleaning of the buffering roll 5 when desired, a cleaning brush 95 (see Figs. 1 and 4) is loosely mounted upon a shaft 97, said shaft being carried at one end of a crank 99, the other end of which is fast to a shaft 101 having at its end a handle 103 by which it may be turned to bring the brush into contact with the roll. A coiled spring 105 having one end fast to the frame of the machine and the other end fast to the hub of the handle 103 normally holds the brush away from the roll.

The operation of the machine is as follows: A sole or other piece of work is fed to the machine from the left as viewed in Fig. 4, the screw 21 having previously been adjusted to determine how much material is to be removed. As the sole is fed beneath the upper front feed roll 27 it raises said roll and through the links 35 raises the rear upper feed roll an equal amount. The first part of this upward movement does not affect the presser roll 45 but as soon as the upward movement has been sufficient to take up the play between the feed roll carrier 25 and the presser roll carrier 47, said presser roll carrier is also raised. It should be noted that the amount which the presser roll is raised is proportional to but less than the thickness of the stock. Consequently as the forward end of the stock reaches the presser roll 45 it raises said roll against the force of the spring 55, and this spring exerts an approximately uniform pressure upon the sole throughout its entire length as it is fed along, it being noted that at no time can the operative portion of the presser roll approach nearer to the plane of the operative portions of the upper feed rolls than the extent of the play or lost motion which originally existed between the feed roll carrier 25 and the presser roll carrier 47. The parts are so arranged that before the rear end of the piece of stock has passed from beneath the forward feed roll 27 the forward end of said stock will have passed beneath the rear upper feed roll 27 so that the action of the presser roll 45 upon the stock will be uniform throughout the extent of said piece. It should be particularly noted that the operative action of the presser roll 45 and the buffering roll 5 will be the same irrespective of the original thickness of the piece of stock and that said thickness does not in any way affect the tension of the spring 55.

Although the invention has been set forth in connection with a particular machine, it should be understood that the invention is not limited in the scope of its application to the particular machine shown and described. In this connection it should be

particularly noted that the automatic adjustment of the presser by the feed roll is not essential to the invention in its broader aspects.

Having thus described our invention, what we claim as new and desire to secure by Letters Patent of the United States is:—

1. A machine of the class described having, in combination, a buffering roll, a presser, means for feeding to said roll and presser a piece of stock, means for moving said presser from said buffering roll a distance proportional to but less than the thickness of said piece, a support for the piece of stock, and means for causing relative adjustment between said support and buffering roll.

2. A machine of the class described having, in combination, a buffering roll, a presser, means for feeding to said roll and presser a piece of stock, means controlled by the thickness of the piece of stock during its passage through the machine for moving said presser from said buffering roll a distance proportional to but less than the thickness of said piece, a support for the piece of stock, and means for causing relative adjustment between said support and buffering roll.

3. A machine of the class described having, in combination, buffering mechanism including a buffering roll and a presser, mechanism for feeding a piece of stock to said buffering mechanism, and connecting means between said mechanisms constructed and arranged to determine the space between the buffering roll and the presser in accordance with the thickness of the piece of stock which is to be operated upon.

4. A machine of the class described having, in combination, buffering mechanism including a buffering roll and a presser, feeding mechanism including separable members, and connecting means whereby movement of one of said separable members causes movement of said presser.

5. A machine of the class described having, in combination, a buffering roll, a presser arranged to hold the stock against the buffering roll, a movable presser carrier, a feed roll arranged to feed the stock to the buffering roll and presser, and a movable feed roll carrier, said presser carrier being located in position to be lifted by said feed roll carrier whereby movement of the feed roll carrier moves the presser carrier.

6. A machine of the class described having, in combination, a support along which a piece of stock may be fed, a buffering roll projecting through said support, a presser arranged to hold the stock against the buffering roll, a movable presser carrier, a feed roll, and a movable feed roll carrier, said presser carrier being located in position to be lifted by said feed roll carrier whereby

movement of the feed roll carrier away from the support moves the presser carrier in the same direction.

7. A machine of the class described having, in combination, a support for a piece of stock, a buffing roll, a presser located above said buffing roll, a feed roll for advancing the stock to the buffing roll, a feed roll carrier, means for permitting said carrier to yield, a presser carrier located above the feed roll carrier in position to be lifted by said feed roll carrier, means for permitting said presser carrier to yield, and means for adjusting said support with respect to said buffing roll.
8. A machine of the class described having, in combination, a support for a piece of stock, a buffing roll extending above said support, a presser located above said buffing roll, a feed roll for advancing the stock to the buffing roll, a feed roll carrier movable away from said support, a presser carrier located above said feed roll carrier and movable in the same direction, a bar located above said presser carrier, a connection between said feed roll carrier and said bar whereby movement of said carrier away from said support is imparted to said bar, yielding means for urging said bar toward said support, and a spring located between said bar and said presser carrier.

9. A machine of the class described having, in combination, a support for a piece of stock, a buffing roll extending above said support, a presser located above said buffing roll, a feed roll for advancing the stock to the buffing roll, a feed roll carrier movable away from said support, a presser carrier located above said feed roll carrier and movable in the same direction, a bar located above said presser carrier, a connection between said feed roll carrier and said bar whereby movement of said carrier away from said support is imparted to said bar, yielding means for urging said bar toward said support, a spring located between said bar and said presser carrier, and means for varying the tension of said spring.

10. A machine of the class described having, in combination, a support for a piece of stock, a buffing roll extending above said support, a presser located above said buffing roll, a feed roll for advancing the stock to the buffing roll, a feed roll carrier movable away from said support, a presser carrier located above said feed roll carrier and movable in the same direction, a bar located above said presser carrier, a connection between said feed roll carrier and said bar whereby movement of said carrier away from said support is imparted to said bar, yielding means for urging said bar toward said support, a spring located between

said bar and said presser carrier, and means for varying the tension of said spring, said feed roll carrier, presser carrier, and bar being carried by said support.

11. A machine of the class described having, in combination, a support for a piece of stock, a buffing roll extending above said support, a presser located above said buffing roll, a feed roll for advancing the stock to the buffing roll, a feed roll carrier movable away from said support, a presser carrier located above said feed roll carrier and movable in the same direction, a bar located above said presser carrier, a connection between said feed roll carrier and said bar whereby movement of said carrier away from said support is imparted to said bar, yielding means for urging said bar toward said support, and means for adjusting said support.

12. A machine of the class described having, in combination, a support for a piece of stock, a buffing roll projecting above said support, a presser located above said buffing roll, a feed roll carrier, a spring urging said carrier toward said support, a presser carrier, a spring urging said carrier toward said support, and a stop for limiting said movement whereby a certain amount of movement of the feed roll carrier away from the support is permitted before the presser carrier is moved.

13. A machine of the class described, having, in combination, a presser, a buffing roll, means for feeding the stock between said presser and roll, and means responsive to the thickness of the stock for separating the presser and roll by a distance such that a predetermined amount will be removed from each piece of stock irrespective of its original thickness.

14. A machine of the class described, having, in combination, a presser, a buffing roll, front and rear feed members for feeding a piece of stock between the roll and presser, connections between the feed members such that movement of one feed member in response to the thickness of the stock moves the other feed member an equal amount, and connections between the presser and the feed members such that the positions of the feed members due to the engagement of either one of them with the stock determines the position of the presser.

In testimony whereof we have signed our names to this specification in the presence of two subscribing witnesses.
